AND COMPANY LIMITED, OF CROYDON, SURREY, ENGLAND

MECHANICALLY ACTUATED VIBRATORY RELAY

Application filed September 24, 1930, Serial No. 484,076, and in Great Britain July 10, 1930.

This invention relates to mechanically actuated vibrating relays as used for telegraphic and like purposes.

In certain relays of this type, on each movement of the armature of a relay from one extreme position to another, mechanical means operate to retroact on the armature, tending to restore it to the position from which it was last moved. The electromagnetic winding of the relay is employed to maintain the armature in one position or the other in opposition to the mechanical retroacting means. In the absence of any controlling current in the winding, the relay armature is maintained in a state of constant vibration between its two positions and at a rate which depends on the speed of response of the mechanical retroacting means. A relay of this description is similar in principle to vibrating relays of the well known Gulstad type, but mechanical instead of electromagnetic retroaction is employed. The mode of operation of such a relay is described in the specification of co-pending application Serial No. 432,828.

When employed on double current circuits, the controlling force in the electromagnetic winding is substantially equal when the relay tongue is in either of its two extreme positions, but when single current working is resorted to, for instance, this controlling force may differ in the two positions according to the design and adjustment of the relay. This will be clear when it is remembered that in double current working, with a relay in neutral adjustment, the armature will be actuated to and held in one position by a current of one polarity, and actuated to and held in the other position by a current of opposite polarity. In single current working, however, the armature is actuated to and held in its operated position by the working current, but when this working current ceases, is returned to its unoperated position either by suitable magnetic biasing or by spring means.

The present invention provides, in vibrating relays with mechanical retroaction, means to adjust the relative strength of the retro-

acting tendency on the relay armature in its two extreme positions.

The means described may be employed, as will be apparent, either for the extreme case of adapting a vibrating relay of this class to single current working or merely for the purpose of adjusting the relative resetting or retroacting tendency in each of the two extreme positions of the relay armature in double current working. In either case the means form a biasing arrangement for the mechanical retroacting means.

Figure 1 of the accompanying drawings represents a mechanically actuated vibrating relay with adjusting means according to the present invention, whilst Figure 2 shows these adjusting means in greater detail.

The mode of operation of the means shown in Figure 1 with the exception of the adjusting means according to the present invention is described fully in the aforementioned specification, but will here be briefly summarized, similar reference numerals being employed for similar parts.

An armature 1 of an electromagnetic relay 2 operates alternately between two extreme positions. At each movement of armature 1, escapement 4 releases member 6 which is yieldingly driven by mechanical power, for half a revolution. An eccentric thus actuates by mechanical power a member 10 alternately from one position to another through connecting rod 9 and lever 8. This arrangement as described, forms a mechanical relay wherein means is operated by mechanical power in accordance with the movements and under the control of armature 1. In Figure 1 this means is shown conveniently as a contact tongue 13 playing between contact screws 11 and 12. Member 14 is also operated by the mechanical relay to slide distance piece 16 alternately between and against spring-pressed independent levers 17 and 18, one extremity of each of which is adapted to engage with armature 1 in opposite directions. The levers 16, 17 thus provide abutment means which engage the armature at opposite ends of its travel and tend to urge it in the opposite direction.

The arrangement is such that each actua-

100

tion of armature 1 from one position to the other is followed by a corresponding movement of distance piece 16 in the opposite direction. The distance piece 16 thus leaves one of the levers 17 or 18 bearing under spring tension against armature 1 and tending to reverse the movement of the armature which has just occurred, and at the same time moves the other lever from operative relation with the armature 1. In other words the parts 1, 16, 17 and 18 move from the position shown by full lines in Fig. 1, into the position indicated by broken lines, or vice versa. In the absence of any current in the relay 2 winding the reverse movement takes place and is followed by another contrary retroacting movement, the relay thus being maintained in a state of constant vibration. The current in relay 2 is thus only required to maintain armature 1 in either of its two positions in opposition to the pressure of the corresponding spring actuated opposing lever 17 or 18, the work of actuating the armature from one position to the other, being performed by mechanical power.

The effective strength of the spring means retroacting on armature 1 in either position is adjusted by screw 24 which bears on lever 23, and tension spring 22 for both levers 17 and 18, but in order to adjust the relative strength of the spring tendency on one lever 17 as compared with that on the other lever 18, means is provided as shown more clearly in Fig. 2. The two levers 17 and 18 are connected by links 30 and 31 respectively to a screwed rod 32 which is rotatable by means of adjusting head 33. Spring 22 is attached to a travelling nut 34 which is adjustably movable from a central position between the links 30 and 31 to one side or the other by head 33.

With the nut 34 in the central position the whole vibrating relay will function as previously described but if it is desired to adapt the arrangement for single current working, nut 34 is adjusted by head 33 towards the link on the opposite side to that in which it is desired that the current should move the relay armature 1. The spring tension through links 30 and 31 is thus unbalanced and the relay will have a bias the extent of which is determined by the position of the nut 34 relative to the central position. In operating on single current, the relay will be actuated to the operated position under the action of the working current together with the tension of spring 22 upon the lightly loaded lever. The mechanical relay then operates and the sliding distance piece 16 moves the lightly loaded lever from operative relation with armature 1 and leaves the more heavily loaded lever pressing against the opposite side of the armature, so that when the current ceases the armature is moved back to the unoperated position by the combined

action of the normal restoring means of the relay and the heavily loaded lever.

It will thus be seen that the relay is relieved of the necessity of operating against the full tension of the restoring means and all the advantages of a vibrating relay of this type are thereby obtainable even in cases where there is normally a difference between the forces acting on the relay armature in the two different directions of movement.

What is claimed is:

1. In a vibratory relay having mechanical retroaction, a pair of levers for applying retroactive forces to the relay armature in its two extreme positions, and means for adjusting the relation of the forces applied to said levers comprising a rod pivotally connected to each of said levers, means for loading said rod and means for adjusting the position of the point of application of the load on said rod.

2. In a vibratory relay having mechanical retroaction, a pair of intermediately pivoted levers, a relay armature oscillatable between and disposed to contact alternately with one end of each lever, and means for urging said ends towards said armature comprising links pivoted to the other ends of said levers, a rod connecting said links, means for applying a transverse load to said rod and means for adjusting the point of application of said load longitudinally of said rod.

3. In a vibratory relay an oscillatable armature, a pair of bell crank levers having a common pivotal axis disposed with one arm of each lever substantially parallel with an arm of the other lever and extending into the path of the armature to provide abutments therefor, and the other arms of the levers extending in opposite directions, links pivotally connected with each of the last mentioned arms, and means for urging the parallelly disposed arms towards the armature disposed therebetween, comprising a rod connecting said links, means for applying a transverse load to said rod intermediate said links, and means for adjusting the point of application of said load longitudinally on said rod.

4. In a vibratory relay, an oscillatable armature, a pair of bell crank levers having a common pivotal axis disposed with one arm of each lever substantially parallel with an arm of the other lever and extending into the path of said armature to provide abutments therefor, and the other arms of the levers extending in opposite directions, links pivotally connected with each of the last mentioned arms, a screw threaded rod rotatably connected to said links, a nut on said rod and traversable therealong and spring loading means attached to said nut.

5. A vibratory relay having an oscillatable armature, movable spring-pressed abutment means disposed to engage said armature at

opposite extremes of its travel, and common adjusting means for differentially adjusting the spring pressures upon said abutment means.

5 6. A vibratory relay having an oscillatable armature, movable spring-pressed abutment means disposed to engage said armature at opposite ends of its travel, common adjusting means for differentially adjusting the pressures upon said abutment means at opposite ends of the travel of the armature and means for increasing or decreasing both said spring pressures simultaneously.

10 7. A relay comprising an armature, a member actuated by mechanical power upon movement of said armature, movable spring-pressed abutment means disposed to engage said armature at opposite ends of its travel and effective in response to the movement of 15 said member to tend to restore said armature into the position from which it was last moved and means for adjusting the relative spring pressure upon said abutment means.

20 8. A relay comprising an armature operable between two extreme positions, a member actuated by mechanical power upon each movement of said armature from one position to the other, spring-pressed means actuated by said member to effect a movement of said 25 armature contrary to its initiating movement in either of its two extreme positions and means for adjusting the relative pressure exerted by said spring-pressed means on said armature in its two extreme positions.

30 35 9. In witness whereof I hereunto subscribe my name this fifteenth day of August 1930.

REGINALD DENNIS SALMON.
